[57] CLAIM

The ornamental design for a barbecue grill, as shown and described.

DESCRIPTION

FIG. 1 is a fragmentary perspective view of a barbecue grill showing my new design;

FIG. 2 is a left-side elevational view of the complete barbecue grill;

FIG. 3 is a rear elevational view of the device as shown in FIG. 1, but shown on a reduced scale;

FIG. 4 is a bottom plan view thereof;

FIG. 5 is a top plan view thereof;

FIG. 6 is a fragmentary perspective view of the barbecue grill with the grill rotated to a broiling position; and

FIG. 7 is a right-side elevational view thereof.
